UNITED STATES PATENT OFFICE.

ALBERT T. FERRELL, OF SAGINAW, MICHIGAN.

BRUSH ATTACHMENT FOR GRAIN-CLEANING MACHINES.

SPECIFICATION forming part of Letters Patent No. 701,865, dated June 10, 1902.

Application filed May 24, 1901. Serial No. 61,716. (No model.)

To all whom it may concern:

Be it known that I, ALBERT T. FERRELL, a citizen of the United States, residing at Saginaw, in the county of Saginaw and State of Michigan, have invented certain new and useful Improvements in Brush Attachments for Grain-Cleaning Machines; and I do hereby declare the following to be a full, clear, and exact description of the invention, such as will enable others skilled in the art to which it appertains to make and use the same.

This invention is a traveling-brush attachment for cleaning the screens of grain-cleaning machines; and the invention consists in certain novel constructions and operation of parts, which will be fully set forth in this specification.

The objects of the invention are, first, to produce a device for operating the traveling brushes of a grain-cleaning machine, which will be simple in construction and operation and not liable to get out of order; second, to provide means for easily and quickly adjusting the pressure of the brush against the screen from outside the machine; third, to provide a mechanism for traversing the brushes back and forth across their screens, and to so construct it that it can be located in any convenient part of the machine where it will be accessible for renewal and repair.

The invention is illustrated in the accompanying drawings, in which—

Figure 1 is a side elevation of a grain-cleaning machine embodying my invention, the frame of the machine being broken away in parts. Fig. 2 is a front elevation of the same. Fig. 3 is a perspective view of the sliding brush-bracket. Fig. 4 is an enlarged section on the line $\alpha-\alpha$ of Fig. 3. Fig. 5 is a front view of the shaft-bracket. Fig. 6 is a side elevation of the same, partly sectional. Fig. 7 is a diametral section of the shaft-carrying cam. Fig. 8 is a front view of the cam. Fig. 9 is a part-sectional front elevation of the brush-carrying device and the traversing mechanism that operates it. Fig. 10 is a part-sectional top view.

As is clearly shown in the drawings, the device consists in a shaft 1 below each screen and extending across the frame of the machine, each shaft carrying a slideable bracket 2, which supports the brush 3 and moves it

sidewise across the under side of the screen 4, which it is to clean.

The object of the shaft 1 is to form a support and guide for the transversely-moving brush. The brush is mounted in the bracket 2, which slides along the shaft 1 from side to side of the machine. The brush, which is usually made equal in length to the length of the screen, is supported intermediate its ends by the shaft 1, so that it may rotate sufficiently to automatically assume an even bearing throughout its length against the under side of the screen. The ends of the shaft 1 are supported by eccentric boxes, so that the shaft can be raised or lowered, thus raising or lowering the brush relatively to the screen, to regulate its pressure against the screen. The details of construction will be described further on in this specification.

In order to move the bracket 2 back and forth along the shaft 1, as above indicated, I connect the bracket with a traversing mechanism constructed in the following manner: 75 Cords 5, parallel with the shaft 1, are fixed at one end to the bracket 2 and at the other end to the transversely-sliding block 6 of the traversing mechanism. This latter mechanism can be located in any convenient part 80 of the machine-frame or outside it if desired. By pulling one of the cords 5 the bracket 2 is slid along the shaft 1 and the brush is moved along the screen to one side, and by pulling the other cord 5 the brush is moved 85 back to the other side of the screen. This movement of the cords 5 is accomplished by moving the sliding block 6 back and forth in its frame 6^a. The function of the sliding block 6 is to impart simultaneous reciprocating movement to the brushes in the machine. The cord 5 passes over a pulley 5^a at each end of the shaft and over pulleys 5^b at each end of the frame 6^a.

As is shown in Figs. 1 and 2, any number of 95 traveling brushes may be secured to and operated by a single sliding block 6. The sliding block is preferably actuated by the mechanism shown in Figs. 9 and 10, in which 6^c and 6^d are sprocket-wheels located near the 100 ends of the frame 6^a and carrying a continuous chain 6^e. One link of this chain carries a laterally-projecting finger or rod 8, which engages the vertical slot 6^b of the sliding block

6. Rotating either of the chain-wheels moves the sliding block along the frame 6^a and im-
parts a corresponding transverse movement
to the brushes connected therewith. When
5 the sliding block reaches either of the chain-
wheels, the link which carries the projecting
finger passes around the wheel, and the hori-
zontal movement of the block gradually
ceases and then reverses as the finger 8 moves
10 vertically in the slot 6^b. By this means the
brush is made to travel uniformly along the
screen from one side to the other, gradually
reducing its speed until it stops at the end of
its travel and then gradually increasing the
15 speed as it commences the return movement,
thus avoiding all shock and noise in reversing.

In practice I prefer to actuate the sprocket-
wheels from the main shaft or other moving
part of the machine by a speed-reducing gear
20 comprising a bevel-gear 9, driven by a pinion
10, which is operated by a pulley 11.

I prefer to mount the shaft 1 in the follow-
ing manner: To each side of the machine-
frame I secure a bracket 12, having an open-
ing 12^a for the passage of the cord 5 and car-
rying a pulley 12^b to guide the cord. The
bracket has a circular opening 12^c, which
serves as a bearing in which is revolvably
mounted the shaft-carrying cam 7, having an
30 eccentrically-located opening 7^a to receive the
shaft. The shaft has a hand-wheel 1^a at each
end, and by means of this hand-wheel the
cam 7 can be revolved, raising or lowering the
shaft as desired to adjust the pressure of the
35 brushes 3 against the screen 4 and to facilitate
the removal and replacing of the screen in the
machine without injury to the brush by the
screen-frame. This movement of the shaft 1
is clearly indicated by the dotted lines in
40 Fig. 5.

In order to prevent particles of grain and
dirt from adhering to the shaft 1 and causing
the bracket 2 to bind as it passes back and
forth along the shaft, I construct the bearing
45 of the bracket 2 as shown in Fig. 4. The hub
13 is cored out or counterbored in the middle
of its length, so as to come into contact with
the shaft at its ends only. The ends of the
50 hub are exteriorly threaded and a packing-
55 gland 13^a is screwed thereon. The space 13^b
between the packing-gland and the end of the
hub is preferably filled with candle-wicking
or similar packing and operates as in ordi-
nary glands to keep the shaft clean and to pre-
55 vent dirt from entering the hub. The pack-
ing is omitted from the drawing for the sake
of clearness.

By the means above described I have pro-
duced a traveling - brush arrangement for
60 grain-cleaning machines, which is simple in
construction, has few moving parts, and can

be easily adjusted or repaired by mechanics
of ordinary skill. When a number of brushes
are used, it is not necessary to duplicate the
driving mechanism, since one sliding block 65
will operate as many brushes as desired, mov-
ing them all simultaneously and with uni-
form speed.

What I claim as my invention, and desire
to secure by Letters Patent, is—

1. A screen-cleaning device comprising in
combination: a brush-carrying bracket slid-
ably mounted on a shaft in proximity to the
screen; an eccentric-carrying bracket at each
75 end of the shaft; an eccentric revolvably
mounted in each of said brackets and sup-
porting the shaft whereby the shaft and
bracket can be adjusted toward or from the
screen; a reciprocating block movable be-
80 tween guides; cords connecting the brush-
carrying bracket with said block; sprocket-
wheels near the extremities of travel of the
block; a sprocket-chain on said wheels, car-
rying a laterally-projecting finger engaging a
85 vertical slot in said block to traverse it along
its guides; and means for rotating said
sprocket-wheels, substantially as described.

2. In a screen-cleaning device the combi-
nation with a shaft parallel with the surface
of the screen and having eccentrics near its
90 ends whereby the shaft can be adjusted rela-
tively to the screen; of a brush - carrying
bracket slidably mounted on the shaft by
means of bearings having packing-boxes, for
removing dirt from said shaft; together with
95 means for traversing said bracket along said
shaft, substantially as described.

3. In a screen-cleaning device, a shaft ar-
ranged parallel with the surface of the screen;
a brush-carrying bracket slidably mounted
100 on the shaft; eccentrics near the ends of said
shaft whereby the shaft can be adjusted rela-
tively to the screen; and means for travers-
ing the brush - carrying bracket back and
forth along said shaft.

4. In a screen-cleaning device, the combi-
nation with a shaft parallel with the surface
of the screen; of eccentrics near its ends
whereby the shaft can be adjusted relatively
110 to the screen; of a brush-carrying bracket
slidably mounted on the shaft by means of a
bearing intermediate its ends which permits
a limited rotary motion around the shaft
whereby the brush may assume an even bear-
ing throughout its length against the under
115 side of the screen, substantially as described.

In testimony whereof I affix my signature
in presence of two witnesses.

ALBERT T. FERRELL.
